UNITED STATES PATENT OFFICE.

ARTHUR G. HATCH, OF DULUTH, MINNESOTA.

FLOOR CONSTRUCTION.

1,415,554.

Specification of Letters Patent. Patented May 9, 1922.

Application filed January 31, 1921. Serial No. 441,202.

To all whom it may concern:

Be it known that I, ARTHUR G. HATCH, a citizen of the United States, residing at Duluth, in the county of St. Louis and State 5 of Minnesota, have invented certain new and useful Improvements in Floor Constructions, of which the following is a specification.

This invention relates to a new and improved method and means for constructing 10 floors of concrete or like material.

In the construction of concrete floors by methods heretofore in general use, the floors have been carried by forms supported upon 15 columns carried by a lower floor. This construction entails the use of a large amount of form and blocking material and involves considerable obstruction to the work. It further renders necessary different lengths 20 of column for each height of room and renders difficult the use of standardized elements.

It is an object of the present invention to provide concrete floor forms and form supporting means which are adapted to be supported upon the walls to be spanned by the 25 floor.

It is a further object to provide supporting means consisting of a collapsible truss 30 structure which may be quickly and easily put in place or removed.

It is an additional object to provide sectional forms which may be readily removed after the completion of the work and used 35 repeatedly.

In a specific embodiment my invention comprises a simple truss structure having certain of its joints pivoted and having its elements detachable at certain points where- 40 by it may be readily collapsed. It further comprises forms adapted for use with these trusses, the forms comprising a plurality of sections, the end sections being provided with curved end portions, thus permitting 45 ready removal.

I have illustrated a preferred embodiment of my invention in the accompanying drawings, in which—

Figure 1 is an elevation showing my truss 50 assembled;

Figure 2 is a plan view of my concrete forms;

Figure 3 is a section on line 3—3 of Figure 2;

Figure 4 is a fragmentary view illustrating one of the upper ends of the truss; 55

Figure 5 is a section on line 5—5 of Figure 4; and

Figure 6 is a fragmentary view illustrating the lower truss joint. 60

Referring to Figure 1, the truss comprises the upper compression member 7, the lower tension member 8, and the transverse compression member 9. The member 7 comprises two sections 10, each provided with 65 connection plates 11, the plates on the two sections overlapping at the middle point of the member and being connected by the cross pin 12. The transverse member 9 has its upper portion fitted upon the pin 12 intermediate the plates 11. Its lower portion, as best shown in Figure 6, is provided with the cap 13 and the longitudinally movable pin 14. This pin 14 is provided with a head 15, which prevents its dropping through the 70 opening in the cap 13. The cross rivet 16 passes through the member 9 and prevents the pin from slipping up into the member beyond a predetermined point. The tension member 8 consists of two sections, each of 75 which is provided with an eye upon its end overlapping the eye of the other section, the eyes 17 fitting about the pin 14. The sections of the member 8 are further provided with adjusting turnbuckles 18. 80

As best shown in Figures 4 and 5, the sections 10 of the upper compression member 7 comprise spaced beams which have their ends secured to the channel member 19 by the screws 20, the channel members serving 90 to retain them in spaced relation. The bolt 21 is passed through the channel member 19 intermediate the members 10. The upper end of each member 8 is provided with an eye 22 encircling its securing bolt 21. The outer face of the channel member 19 has the supporting hook members 24 riveted thereto adjacent its ends. The upper surface of the members 10 carries the form supporting plate 25. As shown in Figure 4, the adja- 95 100

cent edges 27 of the forms are separated by the wedge-shaped wooden strip 31, which is thus cast in the concrete for the purpose of attaching ceilings or other elements.

5 As shown in Figures 2 and 3, the forms consist of a plurality of elements, the central elements 26 being U-shaped in cross section with out-turned edge flanges 27 and being open at the ends. The ends of these members

10 26 are depressed at 28 an amount equal to the thickness of the material in order to receive the ends 29 of the end form elements 30. The outer ends of the end elements 30 are formed upon the arc of the circle, the center 15 of the circle being preferably located approximately in the lower plane of the forms.

In the use of my forms, the truss is placed with its end hooks 24 upon the walls which are to support the floor. The truss is assembled by passing the pin 12 through the plates 11 to connect the two portions of the compression member, the member 9 being also carried by the pin. The eyes of the sections of the tension member 8 are then placed 25 about the pin 14 and the turnbuckles 18 tightened up to render the truss rigid and bring the upper compression member to the horizontal. The forms are then placed in the manner best shown in Figures 2, 3 and 30 5, so that their lateral edges rest upon the top plate 25 of the truss upper member. Due to the overlap of the forms, as shown in Figure 3, the under surface of the concrete floor is smooth. The concrete being poured 35 upon the upper surface of the forms, forms a cross beam above each truss, at which point the floor is most strongly supported by the forms, and lighter connecting floor slabs are formed above the central portions of 40 the form sections.

After the floor has set, the truss is collapsed by loosening the turnbuckles 18 slightly and driving the pin 14 upwardly into the member 9. The pin 12 is then drawn 45 downwardly by the member 9, the upper compression member pivoting about the pin and freeing the hooks 24 from the wall. The central form members 26 are then dropped downwardly, being unsupported, and the 50 end form members may be pivoted about their point of contact with the edge of the wall, as indicated in dotted lines in Figure 1, and then removed.

Obviously, my forms and form supporting 55 construction may be used repeatedly. While I have shown a simple truss, it is quite obvious that any form of truss known to the art may be used, the invention as far as the truss itself is concerned involving the 60 pivoting of certain truss members and rendering certain truss corners easily disconnected so that the truss may be readily collapsed. The forms may be made of any desired width to give any preferred width 65 of floor slab, and, if desired, the adjacent

edges of forms supported upon the trusses may meet or overlap. My collapsible truss may be used to support any type of floor forms, and the several elements of my invention may be modified within the scope of 70 the appended claims in order to adapt them to varying conditions of use.

I claim:

1. A truss adapted for use in supporting concrete forms, the truss comprising longitudinal and transverse compression members and a longitudinal tension member, the tension member comprising sections provided at their adjacent ends with eyes and a pin carried by a transverse member, the pin 75 being movable relative to the transverse member to bring it into or out of engagement with the eyes of the tension sections.

2. A truss adapted for use in supporting concrete forms, comprising a longitudinal compression member consisting of two sections pivotally connected by a pivot member, a transverse compression element having one end pivotally connected to said pivot, and longitudinal tension sections having their 80 adjacent ends separably connected to the transverse compression element.

3. A truss adapted for use in supporting concrete forms, comprising a longitudinal compression member consisting of two sections pivotally connected by a pivot member, a transverse compression element having one end pivotally connected to said pivot, and longitudinal tension sections having their 85 adjacent ends provided with eyes adapted 100 to engage a pin adjustably extending from the transverse compression element.

4. A truss adapted for use in supporting concrete forms, comprising a longitudinal compression element consisting of two sections each formed of two parallel spaced members, the adjacent ends of the sections interfitting and being pivotally connected by a transverse pin, a transverse compression member having an eye engaging the 105 transverse pin, a pin adjustably carried by the opposite end of the transverse element and a sectional tension member, the sections having eyes adapted to engage the pin carried by the transverse member.

5. A truss adapted for use in supporting concrete forms, the truss comprising longitudinal and transverse compression members and a longitudinal tension member, the tension member comprising sections provided at their adjacent ends with eyes adapted to fit against the end of a transverse member and a pin carried by the transverse member, the pin being movable longitudinally of the member to bring it into or out 110 of engagement with the eyes of the tension sections.

6. A collapsible truss adapted for use in supporting concrete forms, the truss comprising longitudinal and transverse com- 115 120 125 130

pression members pivotally associated together, and a longitudinal tension member cooperating therewith, the tension member comprising sections provided at their adjacent ends with eyes adapted to fit against the end of a transverse member, and a pin carried by the transverse member, the pin being movable longitudinally of the member to bring it into or out of engagement with the eyes of the tension sections. ¹⁰

Signed at Duluth, Minnesota, this 24th day of January, 1921.

ARTHUR G. HATCH.
